UNITED STATES PATENT OFFICE.

PAUL R. DE F. D'HUMY, OF CHICAGO, ILLINOIS, ASSIGNOR OF SEVEN-TENTHS
TO ANDREW S. WORK, OF SAME PLACE.

ARMOR-PLATE.

SPECIFICATION forming part of Letters Patent No. 530,024, dated November 27, 1894.

Application filed March 6, 1894. Serial No. 502,484. (No model.)

To all whom it may concern:

Be it known that I, PAUL R. DE F. D'HUMY, a citizen of the Republic of France, residing at Chicago, in the county of Cook and State 5 of Illinois, have invented certain new and useful Improvements in the Method of Constructing Armor-Plates and Certain Parts of Machinery, of which the following is a specification.

- 10 This invention relates to improvements in the method of constructing plates which may be used for armor plates for iron-clad vessels, and also for parts of machinery, such as shaftings, crank-shafts, and fly-wheels; and 15 consists in certain peculiarities of the construction, novel arrangement, and form of the various parts thereof, as will be herein-after more fully set forth and specifically claimed.
- 20 The objects of my invention are first, to provide a means by which the production or manufacture of armor-plate can be accomplished with a minimum of cost and labor, and in a much shorter time, than by the method 25 ordinarily employed; and second, such a construction, which with slight changes, is applicable to parts of machinery, such as large shaftings, fly-wheels, &c.

In order to enable others skilled in the art 30 to which my invention pertains to make and use the same, I will now proceed to describe it, referring to the accompanying drawings, in which--

Figure 1, is a vertical sectional view of a 35 portion of the body of a vessel, showing the construction of my armor-plate and the manner of securing the same thereto. Fig. 2, is a detail perspective view of a portion of one of the sections of the plate and a part of its 40 frame. Fig. 3, is a perspective view of a section of the plate, showing it secured together and ready for its frame, illustrating a modification therein, and Fig. 4, is a similar view of a section of the plate, showing the exterior and interior plates or caps and connecting parts removed. Fig. 5, is a perspective 45 view of the exterior plate or cap detached. Fig. 6, is a perspective view of the inner plate or cap detached. Fig. 7, is a perspective view of one of the sections of the plate, showing it ready for its frame, and illustrating

another modification therein. Fig. 8, is a perspective detail view, partly in section, of one of the sections of the plate and its frame, with the exterior cap removed. Fig. 55 9, is a detail perspective view of the exterior cap used in the modification shown in Figs. 7, and 8. Fig. 10, is a sectional view, taken on line 10, 10, of Fig. 8, showing the method of securing the cap to the transverse slabs. 60 Fig. 11, is a detail perspective view of a portion of one of the sections of the plate, showing a modification in the manner of securing its face plate or cap to the transverse slabs. Fig. 12, is a view in side elevation of a portion of a fly-wheel, embodying my invention. 65 Fig. 13, is a sectional view thereof, taken on line 13, 13, of Fig. 12. Fig. 14, is a plan view of Fig. 12. Fig. 15, is a view in elevation of a portion of one of the spokes of the fly- 70 wheel. Fig. 16, is a similar view of a portion of the hub. Fig. 17, is a similar view of another part of one of the spokes of the fly-wheel. Fig. 18, is a view in elevation of another part of the hub. Fig. 19, is a perspective 75 view, partly in section, of a portion of a crank-shaft, showing my invention embodied therein. Fig. 20, is a like view of another part thereof, and Fig. 21, is a perspective view of a portion of the same. 80

Similar letters refer to like parts throughout the different views of the drawings.

A, represents a cap or exterior plate of steel or metal of any desired dimensions, but preferably rectangular in form. The inner surface of this plate is provided with a number of transverse grooves *a*, and corresponding projections *a'*, within which grooves and against the ends of the projections fits and rests a series of alternately wider and narrower metal slabs B, which slabs are provided at suitable points with holes *b*, and *b'*, so that the said holes or openings shall be in a line drawn across the slabs B, or transverse plates. By reference to Fig. 1, of the drawings, it will 95 be seen that the holes *b'*, in every alternate slab is larger in diameter than the holes or openings *b*, in the intervening plates. The slabs B, and the plate A, are placed together, as shown in Figs. 1, and 2, and the frame consisting of a series of slabs or sheets C, in the shape of nested boxes is placed around the 100

same, and the exterior plate A, is held in position by means of the bolts C', which pass through the sides of the frame C and through registering holes in the projections a' and 5 wider slabs B. The rear portion or opposite side of the frame C, from the plate A, is provided with openings or seats c, for the reception of bolts D, which pass through the backing D', and are secured within the hull of 10 the vessel. The frame C, is also provided at suitable points to correspond with the openings b, and b', with similar openings b² through which melted metal is poured into the openings b, and b', of the slabs B, where when it 15 becomes cool it will join the slabs into a compact and almost solid mass. Between the rear side of the frame C, and the backing D', is placed a series of tubes E, having within them similar tubes E', between which is placed suitable packing. These tubes are to furnish 20 resistance to the force of the projectile thrown against the plate A, and as is well known greater strength is attained by the cylindrical form of the tubes, and by having one 25 within the other, if the outer one should become broken, the inner one will still resist the force. It is obvious that if the plate A is destroyed by a projectile, it can be readily removed, and a new one replaced. It is 30 also obvious that by employing the series of slabs B, placed transversely with the plate A, greater strength is acquired, and as the slabs are divided one from the other, that the force of the projectile striking against the plate A, 35 will be distributed, and thereby rendered less effective. The frames C, are united together on their inner surface by means of suitable bolts C², or in any desired manner.

In Figs. 3, to 6, inclusive, I have shown a 40 modification of the construction of the armor-plate, in which the alternate slabs B', are fitted into grooves a, of the plate A', as above described, and are secured together by means of bars B⁵, extending across the group of 45 slabs at points preferably about midway between their front and rear ends; while the projections of the exterior plate or cap A' may be secured to the wider slabs B' by plain bolts or keys, or by means of melted metal 50 inserted in the openings a², passing transversely therethrough. That portion of the slabs B', in this modification adjacent to the vessel is provided with a cap or interior plate A², having recesses a³, and corresponding projections a⁴, which unite with projections a⁵, and recesses a⁶, at the rear edges of the slabs. 55 Transversely to the said recesses and projections the slabs are formed with recesses a⁷, within which fits the transverse extension a⁸, 60 on the interior cap A², or plate. When the caps or plates A', and A², and slabs B', are united, as shown in Fig. 3, they will form a compact section, which may be inclosed in a frame, as before described and secured to the vessel. 65

In Figs. 7, to 10, inclusive, is shown still another modification, in which the slabs B²,

are placed transversely against the inner surface of a series of slabs A³, which form the exterior plate in this case, and which latter named slabs are formed with grooves a, and for the reception of the ends of alternate slabs B², as shown. The slabs B², are held together by means of bars or melted metal inserted in the openings e, which unite them together, and with the inclosing frame C, or box. The series of slabs A³, forming the exterior cap or plate is secured to the series of slabs B², by means of bars or melted metal d⁵, which are passed transversely through the openings d⁶, in the projections d⁷, of the slabs B²; and around the united parts may be placed a frame C as before. 70 75 80 85

In Fig. 11, is shown another manner of securing the plate to the transverse slabs, which 85 consists in forming the plate A⁴, with dovetail mortises c⁵, within which is fitted correspondingly formed projections f, on the ends of the transverse slabs.

In Figs. 13, to 18, inclusive, I have shown 90 the method of employing my invention to the construction of the various parts of a fly-wheel, which consists in laying a series of strips of metal of the requisite form, to form the periphery of the wheel, the spokes, and 95 hub thereof, and providing said strips with openings, through which is passed bars or melted metal for securing them together.

In Figs. 19, to 21, inclusive, is shown portions of a crank-shaft, in which the same 100 method of construction is employed, as above described in the fly-wheel.

Having thus fully described my invention, what I claim as new, and desire to secure by Letters Patent, is—

1. As an improved article of manufacture, 105 an armor made in sections each consisting of a group of slabs secured together and standing edgewise to the impact, a frame surrounding the sides and rear of each group and consisting of a set of nested boxes, and means for securing the frame to the slabs.

2. As an improved article of manufacture, 110 an armor made in sections each consisting of a group of slabs secured together and standing edgewise to the impact, a frame surrounding the sides and rear of each group, and an exterior plate secured to the outer edges of the slabs.

3. As an improved article of manufacture, 115 an armor made in sections each consisting of a group of alternately wider and narrower slabs secured together edgewise to the impact, and an exterior plate of the size of the group having alternate projections and 120 grooves on its inner face engaging the outer edges of the slabs, and bars passing through aligned holes in the projections of the plate and the wider of the slabs.

4. As an improved article of manufacture, 125 an armor made in sections each consisting of a group of slabs secured together edgewise to the impact, an exterior plate of the size of the group secured to their outer edges, and

an interior plate of the size of the group secured to their inner edges.

5. As an improved article of manufacture, an armor made in sections each consisting of a group of slabs secured together edgewise to the impact, an exterior plate of the size of the group secured to their outer edges, an interior plate of the size of the group secured to their inner edges, a frame surrounding the sides and rear of the entire section, and means for securing it to the slabs.

6. As an improved article of manufacture, an armor made in sections each consisting of a group of slabs secured together edgewise to the impact, an exterior plate composed of a number of slabs also secured together edgewise to the impact and standing in planes at right angles to the planes occupied by the slabs, and means for connecting the exterior

20 plate with the group.

7. As an improved article of manufacture, an armor made in sections each consisting of a group of slabs secured together edgewise to the impact, an exterior plate composed of a number of slabs also secured together edge-

wise to the impact and standing in planes at right angles to the planes occupied by the slabs, means for connecting the exterior plate with the group, a frame surrounding the sides and rear of the group, and bars passing 30 through the sides of the frame and transversely through the slabs in the group.

8. As an improved article of manufacture, an armor section consisting of a group of alternately wider and narrower slabs set edge- 35 wise to the impact and secured together, an exterior cap consisting of a number of plates also set edgewise to the impact and standing in planes at right angles to the planes of the slabs, the rear edges of the plates being 40 formed with projections and grooves to engage the front edges of the slabs, said plates and slabs being formed with transverse openings through their interlocking portions, and bars passed through the aligned openings.

PAUL R. DE F. D'HUMY.
